United States Patent Office.

HENRY S. FORNEY, OF BALTIMORE, MARYLAND.

Letters Patent No. 63,030, dated March 19, 1867.

IMPROVED WASHING MACHINE.

The Schedule referred to in these Letters Patent and making part of the same.

TO ALL WHOM IT MAY CONCERN:

Be it known that I, HENRY S. FORNEY, of the city and county of Baltimore, and State of Maryland, have invented certain new and useful improvements in Washing Machines; and I do hereby declare the following to be a full, clear, and exact description of the same, reference being had to the accompanying drawings, making a part of this specification, in which—

Figure 1 represents a vertical section through the machine, showing the gearing partly in elevation and partly in section.

Figure 2 represents a section through a portion of the machine, and taken at right angles to that shown in fig. 1.

Figure 3 represents a section taken through the bevel pinion and shaft at the red line $z z$ of fig. 1.

Similar letters of reference, where they occur in the separate figures, denote like parts in all the drawings.

In using metallic gearing in washing machines, the tub or box of which is made of wood, and the gearing attached to the lid thereof, it is found that the swelling, shrinking, or warping of the wood, on account of its frequent contact or saturation with hot and cold water, cramps the gearing, or causes it to bind so as to run very hard, and frequently to break down. My invention consists in so constructing and uniting the gearing and its supports with the lid and shaft, as that the yielding or warping of the wood will not affect the gearing, or cause it to bind, cramp, cut, or break, the connections and bearings being metallic, or so arranged as not to be influenced by the shrinking or warping of the wood.

To enable others skilled in the art to make and use my invention, I will proceed to describe the same with reference to the drawings.

A represents a tub, which is in the form of a frustum of a cone, with a head, B, and bottom, C, in it, and made of staves in the ordinary way. Inside of the tub I arrange a series of standards or rollers, D, against which the clothes are thrown or carried in washing them. In the head or top B of the tub there is a hinged lid, E, through the opening covered by which the clothes to be washed are put in, and when washed removed. This much of the machine may be made in any well-known way, shape, size, or form. My invention relating more particularly to the gearing, I shall proceed to describe that part more minutely.

On top of the lid E are two metallic standards or pillar blocks, F, in which the journals $a a$ of the main driving cog gear-wheel G rest and rock or turn, said gear-wheel having cogs only on a part of its face, though they may extend clear around, and the wheel be turned by a crank instead of being rocked back and forth by the lever or handle H, as shown in the drawings.

The pinion-wheel I, which the wheel G gears with and turns, has upon it, first, its bevel teeth b ; secondly, a web or rib, c ; thirdly, a hub or socket, d ; and fourthly, a shoulder, e , the uses of which are as follows: The teeth or cogs to give it motion; the web to secure it firmly to the top of the shaft J that carries the agitators K for moving the clothes around against the columns, posts, or rollers, D, and turning them over; the hub or socket for receiving the upper end of the shaft J, and the shoulder for forming a bearing on and in a metallic collar, f , that is flanged at its top; and is let into the lid E to form the support on which the shaft and agitators or arms K are suspended. A pin, g , may pass through the hub, shaft, and journal, m , which latter may be cast on to or made a part of the web, and which has a bearing in a projection, n , on one of the pillar blocks F.

The arms or agitators K pass obliquely through the shaft J, and are so made that they will swing out of the opening covered by the lid E when the lid is raised up. I thus make a simple, cheap, and durable form of gearing which is not liable either to cramp, wear out, or break.

Having thus fully described my invention, what I claim therein as new, and desire to secure by Letters Patent, is—

In combination with a flanged metallic collar, f , in the lid E, the bevel pinion or gear I, made, arranged, and operating therewith, and with the drive-gear and the agitator or stirrer, substantially in the manner and for the purpose described.

HENRY S. FORNEY. [L. s.]
